CONVERSION OF HYDROCARBONS

Arthur E. Pew, Jr., Bryn Mawr, Pa., assignor, by
mesne assignments, to Houdry Process Corpora-
tion, Wilmington, Del., a corporation of Dela-
ware.

Application November 20, 1936, Serial No. 111,780

18 Claims. (Cl. 196—48)

The present invention relates to the art of treating or converting hydrocarbons and especially to the production from starting material containing higher boiling hydrocarbons of valuable, high anti-knock lower boiling hydrocarbons of the benzine, naphtha or gasoline type. It is particularly concerned with the production of such lower boiling hydrocarbons from hydrocarbons which contain both difficultly vaporizable material of the type found in heavy fuel oils or in crude petroleum distillation residues and easily vaporizable distillate materials of the type of gas oil and the like.

Various systems for effecting pyrolytic or thermal conversion of hydrocarbons into valuable products of the gasoline or motor fuel type are known and several such systems which differ from one another in only minor respects are in common use. These systems are capable of handling fresh and/or partially converted clean distillate or easily vaporizable materials with reasonable facility to make therefrom acceptable yields of good anti-knock motor fuels. When working on heavy charging stocks or material containing substantial amounts of difficultly vaporizable hydrocarbons, however, these systems can produce good anti-knock motor fuels directly from such stocks only at relatively great sacrifice of yield with attendant high yields of coke and gas. The motor fuels so produced from the heavy charging stocks are often dark in color and/or sour and are consequently relatively difficult to refine. The relatively high yields of coke require frequent shutting down of the system for the purpose of removing accumulated coky deposits therefrom. In order to minimize coky deposits and to otherwise facilitate handling of these heavy materials, refiners have heretofore resorted to two or more cracking steps: first, one or more viscosity breaking operations to form crackable gas oil and extremely heavy residuum, and, second, a cracking operation to convert the gas oil so formed into gasoline and further tarry bottoms.

Another type of system involves the use of absorbent and/or adsorbent contact masses capable of promoting the desired reactions and of retaining therein and thereon any reaction products of a gummy, gum forming, coky or coke forming nature so that the products passing therefrom are clean and are comprised essentially of easily vaporizable materials. After separation of the desired lower boiling hydrocarbons from the products the remaining residue has the characteristics and uses of clean distillates of the gas oil

type. The contact mass or catalyst gradually loses activity as the deposit accumulates and requires periodic renewal or regeneration to effect removal of the deposit. Such systems usually perform to best advantage in vapor phase on successive and distinct passes on fresh charge and segregated residues under increasingly severe reaction conditions and generally produce the best yield of lower boiling hydrocarbons during the first pass, i. e., from fresh or original charge. They produce high yields of good anti-knock lower boiling hydrocarbons which are relatively easily refined directly from difficultly vaporizable charging stocks containing substantial amounts of materials which are resinous or coky in nature or which tend to produce resinous or coky substances without any preliminary cracking or viscosity breaking operations, as well as from easily vaporizable clean distillate stocks. In order to effect vaporization of the high boiling portions of the residual charging stock without substantial pyrolytic cracking thereof and/or to maintain vapor phase conditions during the operation it is usually necessary to employ an inert diluent fluid which lowers the partial pressure of the charging stock. Such fluids increase to substantial extent the volume of material handled by fractionating equipment and their use requires fractionating columns and auxiliary equipment which are extremely large and expensive to operate.

One object of the present invention is advantageously to combine a catalytic system with a pyrolytic system, so that the advantages of each are secured and disadvantages minimized or eliminated. Another object is to effect economies of heat and of equipment. Other objects will be apparent from the detailed discussion which follows.

A quick understanding of the invention may be had by referring to the illustrative embodiment thereof shown in the accompanying drawing.

The drawing shows a catalytic reaction zone indicated by reference character A and enclosed by a broken line and a thermal or pyrolytic reaction zone B set off by a dot and dash line. Reaction zone A contains a catalytic system of any known or desired type providing one or more reaction vessels containing absorbent and/or adsorbent contact material capable of promoting transformation of higher boiling hydrocarbons into clean, easily vaporizable products having distillate characteristics and uses, including good antiknock lower boiling hydrocarbons of an easily refinable nature. Reaction zone B provides one

or a plurality of pyrolytic conversion systems of any known or desired type.

Catalytic zone A and pyrolytic zone B are each connected to a fractionator for fresh charging stock such as fractionating column 1 and with a products fractionator such as fractionating column 2 to provide unitary apparatus, all elements of which function continuously, simultaneously and interdependently in producing good anti-knock lower boiling motor fuels, such as gasoline, from charging materials containing both difficultly vaporizable and easily vaporizable hydrocarbons, as exemplified by whole petroleum crude oil, topped crude and various blends of distillate and residual stocks which may be made or may occur in refinery practice. Fractionating column 1 receives fresh charge and divides it into one or more distillate fractions comprising essentially easily vaporizable hydrocarbons which provide charge to pyrolytic zone B and into a residual fraction containing substantially all of the difficultly vaporizable material in the charge, with or without substantial amounts of lower boiling components, which is fed to catalytic zone A. Thus pyrolytic zone B handles only materials of the type which it is capable of converting to best advantage into easily refinable lower boiling hydrocarbons of high antiknock rating and which causes a minimum of shut-downs for removing accumulated deposits of coke and the like, while the difficultly vaporizable materials are transformed by the system capable of producing from them the maximum amount of products of highest quality and value, including sweet, high anti-knock lower boiling hydrocarbons and clean higher boiling hydrocarbons having distillate characteristics and uses. The lower boiling hydrocarbons made in both zones A and B are separated from higher boiling material in fractionator 2 to provide a blend of catalytically transformed and pyrolytically converted products.

According to one aspect of the invention, all or substantially all of the reaction products or synthetic crude produced in one zone pass directly into products fractionator 2. The reaction products or synthetic crude from the other zone are, on the other hand, cooled in several stages, preferably by passing them in heat exchange relation with controlled amounts of cold or relatively cold streams of material fed to or occurring in the process, to provide a plurality of somewhat roughly separated condensates having differing boiling range characteristics, namely, in the order of their production, one or more liquid fractions comprising essentially clean higher boiling hydrocarbons, and a liquid fraction comprising desirable lower boiling hydrocarbons, permissibly having therewith a small amount of higher boiling hydrocarbons, as for example, of the light gas oil or heavy naphtha type. After separation of fixed gases and any extraneous material such as water therefrom the latter fraction is admitted in liquid phase to products fractionator 2 at or adjacent the top thereof to act as a refluxing agent therein and to be separated into higher and lower boiling hydrocarbons with the material from the first mentioned zone. The above procedure secures economies of heat and equipment in addition to the above indicated advantages of the combined pyrolytic and catalytic systems. Heat that is ordinarily lost to the process by returning to a fractionating column, as reflux, part of the condensed overhead from the column is, according to this invention, retained in the system and used to advantage in the proc-

ess. Furthermore, products fractionator 2 and the heat exchanging means following it handle a minimum of material and thus provide for decreased first investment and operating costs.

In the embodiment of the invention disclosed in the drawing, fresh hydrocarbon charge, for example, a whole crude, is heated to distillation temperature in heater 3 and is conducted through line 4 to fractionator 1 wherein it is divided into an overhead cut, two side stream distillate fractions and a residue which leave the column by lines 5, 6, 7 and 8, respectively. The overhead fraction in line 5 contains lower boiling hydrocarbons which it is not necessary or desirable to convert. The side stream distillate fraction leaving column 1 by lines 6 and 7 are charged preferably separately but permissibly together to pyrolytic zone B and may be a naphtha fraction and a gas oil cut or relatively light and relatively heavy gas oil cuts. Pyrolytic zone B is shown as containing three pyrolytic conversion units, indicated by cracking furnaces 9, 10 and 11, selectively connected to fractionator 1, so that any one or any combination of these units may effect the desired conversion of the fractions in lines 6 and 7. These pyrolytic conversion units are also selectively connected to line 12 and discharge reaction products into the latter which conducts them into fractionator 2, shown provided with an outlet 13 for partially converted higher boiling hydrocarbons or inconvertible cracked residuum such as tar and the like, one or more side stream outlets such as lines 17, 14 and 48 for heavy naphtha, light gas oil and heavy gas oil fractions, respectively, and an overhead vapor line 15 for desired end point lower boiling hydrocarbons and fixed gases.

The residue leaving fractionating column 1 by line 8 is charged to catalytic zone A. This stock has had removed from it practically all of the material which it is possible to vaporize at the non-cracking or low cracking temperatures which usually exist in the furnace 3. It is therefore necessary, in order to produce further cracking stock, which will be free of heavy or tarry constituents, from the heaviest portions of this residue, to subject it to a different set of conditions than those existent in furnace 3 and tower 1. If the residue is heated to a higher temperature than that to which the crude was heated in furnace 3, cracking of the heaviest material will take place with the production of low boiling stocks including gasoline of an inferior quality. This operation, however, would not produce sufficient stock in condition to be properly cracked in the catalytic zone. Steam or other suitable inert diluent fluid is therefore used, because of the partial pressure effect produced, in order to vaporize the desired stock without cracking the heavy ends of the residue in the process.

As shown in the attached drawing, this stock is forced by means of pump 16 through the coil within the furnace 11, wherein it is heated to substantially the desired final temperature and from 10 to 20% by weight of steam is added by injection into the coil through line 41, the amount of steam used at this point being dependent upon the characteristics of the individual charge and upon the temperature to which it is desired to raise the charge in furnace 11. The steam so added is preferably superheated steam at substantially the same temperature as the stock flowing through that portion of the coil into which the steam is injected. After the injection of the steam, the oil and steam are still further

heated and passed to a vaporizer or tar separator 18, wherein vaporized material is separated from the tarry bottoms which are withdrawn by line 19. The mixed oil vapors and steam then pass through line 20 to one or more of the catalytic converters 21 selectively connected to line 20 and containing contact mass capable of promoting the desired transformation of the vapors. During the passage of vapors through line 20, additional steam, as up to 10% by weight of the charge to zone A is injected through line 42. The steam so injected is at least at the same temperature as the mixed oil and steam in line 20, but is preferably at a slightly higher temperature. In normal operation 15% or more of steam is utilized which is added as preferred either by line 41, or partly by line 41 and the remainder by line 42.

It is well known that when a mixture of fluid and vapor is discharged into a separator and the vapor taken overhead, such vapor contains small particles of liquid in the form of a mist. If such vapor is then subjected to a cracking reaction the small liquid particles in the vapor readily form coke during the cracking reaction. For this reason the steam is injected through line 42 to dry the vapors by furnishing sufficient heat and partial pressure effect to secure the vaporization of any liquid oil in the form of mist remaining in the vapors.

The cracked vapors flow from the catalytic chambers 21 through line 22 and are cooled in a succession of steps in heat exchangers 23 and 24, wherein a very rough fractionation takes place, wide range gas oil cuts of relatively heavy and relatively light nature being removed through lines 28 and 29, respectively, and a distillate containing all of the cracked gasoline and a portion of the heavy naphtha from the top of heat exchanger 24. Such fractionation must be resorted to due to the immense volume of vapors which it is necessary to handle because of the addition of steam through lines 41 and 42. When 10% steam is added through line 41 and 5% additional steam injected through line 42 the volume ratio of steam to condensable oil vapors in line 22 is of the order of 1.75:1 while the presence of fixed or incondensable gases further augments this ratio. If desired, the fractions leaving heat exchangers 23 and 24 by lines 28 and 29 may have entrained lower boiling hydrocarbons removed from them in steam strippers 30 and 31. The use of such strippers increases further the amount of steam mixed with the distillate fraction issuing from the top of heat exchanger 24.

Although steam is the most satisfactory inert diluent, others are suitable, including fixed hydrocarbon gases, such as those made in cracking and other refinery operations. When refinery gases are used, even larger volumes of them are required than of steam to give the desired partial pressure effect.

If ordinary fractionation in a distillation tower was employed it would require so large a tower and auxiliary condensing equipment as to make the process uneconomic from an investment standpoint and expensive to operate. However, by employing the partial condensing heat exchangers 23 and 24 and the exchanger 25, which latter is in some instances augmented by cooler 31, it is possible to roughly fractionate into two gas oil cuts and a cracked distillate. The cracked distillate after separation from the water and fixed gas in separator 32, is removed through line 33 and forced by pump 34 to fractionating tower 2, wherein it is used as a refluxing liquid

to supplant that ordinarily furnished by condensing the overhead vapor fraction taken off through line 15. In fractionating towers following cracking units the reflux rate may vary from 3:1 to 8:1, depending upon the degree and accuracy of fractionation desired, and also upon the materials fed to the tower for fractionation. The ratios herein stated are volume ratios; reflux to condensed overhead product. If sufficient reflux is not available for fractionation in tower 10 2 in the material passing to the tower through line 33, additional make-up material may be withdrawn from the condensate produced in condenser 35, as from gas separator 36, and passed back to the top of the tower 2.

According to the accompanying drawing, the fresh charge is used as the heat exchange medium in the rough fractionation of the catalytic synthetic crude. To effect this, fresh charge, supplied by line 26, prior to its admittance to heater 3, is forced by pump 27 through serially connected heat exchangers 25, 24 and 23 counter-currently to and in heat exchange relation with the catalytic synthetic crude. By use of the valved by-pass lines around each of these exchangers the amount of heat exchange in each may be so regulated that a controlled and predetermined portion of the catalytic synthetic crude is condensed in each. In order to effect controlled fractionation in column 2, it is sometimes desirable to cool the vapors entering therein by line 12. In such instances the desired amount of cooling may be done by the use of a heat exchanger such as 43 through which controlled amounts of fresh charge may be passed, 30 by proper use of valved by-pass 44. When the bottoms or residual fraction of the fresh charge is unusually large and/or very large amounts of steam are required in catalytic zone A, the cooling capacity of the fresh charge may be augmented by an auxiliary cooler, such as cooler 37, provided with valved by-pass 38 therearound.

Clean higher boiling hydrocarbon condensate produced by partial condensation of synthetic crude issuing from one of the reaction zones, as for example and by preference the higher boiling condensate derived from catalytic synthetic crude leaving heat exchangers 23 and 24, by lines 28 and 29, after being stripped of lower boiling hydrocarbons, or not, as desired, may be charged to pyrolytic zone B for conversion separately or suitably mixed with distillates leaving column 1 by lines 6 and 7, these condensates being conducted through lines 39 and 40 connected to strippers 30 and 31 and to zone B. When a very high degree of conversion is desired, one or more cuts of material having heavy naphtha and/or gas oil characteristics may be taken from fractionator 2 and reconverted. For realization of the best yields of highest quality products therefrom it is preferable that such fractions and particularly the heavy naphtha and heavy gas oil fractions be converted separately as in separate and distinct conversion systems or units, as for example in zone B, maintained under 65 reaction conditions best suited for each particular fraction, but it is permissible to convert these fractions along with other fractions occurring in the process. The drawing shows illustrative connections for conducting to pyrolytic zone B 70 the light gas oil fraction issuing from fractionator 2 by line 44. Line 45 permits this fraction to be charged to pyrolytic zone B either separately or with any other stream of material entering zone B. Pyrolytic zone B is adapted 75

for any desired type of operation. For example, each fraction to be converted in this zone may be treated separately in a separate conversion system or unit, or one or more streams of charging material to this zone may comprise a desired blend of selected materials and may be, for instance, a desired blend or blends of any desired number of virgin or unconverted distillates issuing from column 1 or any desired blend 10 of unconverted and partially converted or transformed distillate materials, as for example, a blend of virgin gas oil with a gas oil fraction produced from partial condensation of one of the synthetic crudes and/or a gas oil cut such 15 as that leaving fractionator 2 by line 14. Furthermore, streams of charging material to zone B may be shifted from any unit to any other to permit cleaning of any unit and to secure continuous operation without requiring cessation 20 of operation of the combined pyrolytic and catalytic zones for cleaning out pyrolytic conversion units.

The conversion unit or units employed in pyrolytic zone B may be of any known or desired 25 type for effecting conversion of higher boiling hydrocarbons into lower boiling hydrocarbons in the vapor phase, liquid phase or mixed phase and may involve internal recycling of partially converted material or may be utilized in straight 30 pass operations. Suitable processes and equipment includes processes and apparatus known as the Cross, Dubbs, tube and tank, De Florez, true vapor phase, gyro, and Holmes-Manley systems, or any high pressure true liquid phase process. 35 The operating conditions employed in this zone vary with the characteristics of the charge and with the type of pyrolytic system used. Suitable temperatures usually lie within the range of 750° F. to 1200° F., while the pressures may 40 range from atmospheric or slightly below to 2500 lbs. per sq. in. or higher.

The contact mass employed in catalytic zone A may be any absorbent and/or adsorbent material capable of aiding the desired reactions. 45 Good results are usually obtained with contact masses comprising or containing materials of siliceous nature or origin, derived from naturally occurring or artificially prepared substances, with or without the inclusion or addition of desired amounts of active or modifying ingredients. 50 Suitable contact masses include blends of silica and one or more metal oxides capable of assisting in the transformation reactions and/or of promoting regeneration. The blend may be derived from naturally occurring materials or from 55 precipitated or non-precipitated gels comprising or containing mixtures or compounds of silica and one or more metal oxides. Excellent results have been realized with contact masses containing blends of silica and alumina of artificial origin or derived from naturally occurring silicates and hydrosilicates of alumina, including activated blends of silica and alumina in controlled ratio with or without other ingredients, as for example, contact masses wherein the silica and alumina are in the weight ratio of at least 3:1, after 60 the manner described in the copending applications of E. J. Houdry, Serial No. 600,581, filed March 23, 1932, (Patent No. 2,078,945, granted 65 May 4, 1937) and Serial No. 35,101, filed August 7, 1935 (Patent No. 2,078,951, granted May 4, 1937). In order to facilitate regeneration the contact masses may be in the form of fragments or molded pieces, as indicated in the above mentioned applications.

The catalytic system in zone A may be of any known or desired type employing one or more converters of any known or desired construction, in which, for example, the contact mass may be arranged in tubes, as annuli, in layers, or as a single body. The converters may be arranged and adapted for use alternately in transformation of the charge and in regeneration of the contact mass in place or, though less advantageously for periodic discharge of the contaminated contact 10 mass and recharging of fresh or regenerated catalyst. The heat necessary for vaporizing the charge and raising the same to reaction temperature may be added wholly or partially in an auxiliary heater, such as heater 17, which may 15 be of the tubular type. Alternatively, contact vaporizers, such as disclosed, for example, in U. S. Patent No. 1,989,927 issued to E. J. Houdry on February 5, 1935 may be substituted for both heater 17 and tar separator 18. Satisfactory arrangements of the catalytic zone A include two converters, as shown, or a multiplicity of converters, as indicated in U. S. Patent No. 2,031,600, of James W. Harrison and Thomas B. Prickett, issued February 25, 1936. The best operating 25 conditions for catalytic zone A will vary with the source and type of both charging stock and contact mass. Suitable temperatures and pressures for efficient transformation of most residual stocks utilizing catalysts comprising essentially 30 blends of silica and alumina usually lie within the ranges of 750° F. to 925° F. and atmospheric pressure to about 75#/sq. in., respectively.

The following example is given as typical to further illustrate the invention.

An East Texas Crude was divided in an initial fractionator such as fractionator 1 into (1) an overhead cut containing a straight run gasoline of about 300° F. E. P. representing about 15% of the crude; (2) a heavy naphtha fraction boiling 40 substantially completely in the range of 250° F. to 420° F. representing about 22% of the original charge; (3) a clean, distillate gas oil cut representing about 26% of the crude and boiling substantially completely within the range of 400° F. 45 to 700° F.; and (4) a high boiling residue or bottoms cut containing substantially all difficultly vaporizable material in the charge and representing approximately 37% of the fresh crude. The heavy naphtha cut and the gas oil fraction were 50 converted separately in single pass operations in a pyrolytic reaction zone, as in units 9 and 10 in zone B, the naphtha being subjected to a temperature of the order of 900° to 930° F. and a pressure of approximately 1375 lbs. per sq. in. 55 for approximately 90 seconds to effect reforming or improvement in the antiknock rating thereof, and the gas oil being subjected to the action of temperature and pressure of about 890° F. and 1750 lbs./sq. in. respectively, for about 3 minutes 60 to produce good antiknock lower boiling hydrocarbons. Coincidentally with the conversion of the naphtha and gas oil fractions the residue was 65 transformed in a catalytic zone such as zone A. Before admittance to the catalytic zone the residue was admixed with about 10% steam by weight thereof was heated to a temperature of the order of 890° F. as in heater 17 to effect vaporization of a substantial proportion of it. Unvaporized material to the extent of about 6% of the original 70 crude was removed from the vapors in a suitable separator such as separator 18 as a heavy tar leaving the latter by line 19 and having a specific gravity of about 1. The vapors issuing from separator 18 by line 20 under a pressure of the 75

order of 15 lbs./sq. in. gauge after addition thereto, as by line 42, of superheated steam to the amount of about 5% by weight of the residue, were charged to a converter, such as one of the 5 converters 21, containing a catalyst comprising essentially a blend of silica and alumina in the weight ratio of about 3½ to 1 and maintained at a temperature of about 860° F. The rate of feed of detarred vapors to the converters was 10 of the order of 3:4 (3 volumes of condensed vapors per hour to 4 volumes of contact mass). Reaction products from both zones were fractionated in a single products fractionating column such as column 2, those from the pyrolytic 15 zone being discharged directly into the column at a point adjacent its bottom as through line 12. The catalytic reaction products were subjected to a series of controlled cooling steps by passing them through a series of heat exchangers such as exchangers 23, 24 and 25 in heat exchange relation with the relatively cold fresh crude to produce, as condensate, two roughly separated higher boiling hydrocarbon fractions suitable for use as domestic or Diesel fuel oils 20 or as cracking stock, namely, a relatively heavy gas oil, condensed in partial condensing heat exchanger 23 and withdrawn therefrom by line 28, a relatively light gas oil fraction condensed in partial condensing heat exchanger 24 and withdrawn by line 29 and a liquid fraction comprising essentially lower boiling hydrocarbons of the motor fuel type produced in heat exchanger 25. After being stripped of entrained lower boiling hydrocarbons in strippers 30 and 31 the gas oil 30 fractions had boiling ranges of the order of 600° to 750° F., and 450° to 650° F. The light fraction was conducted by line 40 and added to the gas oil distillate cut in line 1, passing to pyrolytic still 10. The heavy distillate fraction was conducted by line 39 for conversion separately in cracking unit 11 at a temperature of about 880° F. and pressure of about 1750#/sq. in. for about 3 minutes. The remaining fraction comprising about 85% hydrocarbons boiling below 400° F. and about 15% light gas oil, after removal of 40 fixed gases and condensed water therefrom, in separator 32, was fed, in liquid phase, by line 33 into the product fractionator at a point adjacent the top thereof wherein it acted as reflux and was divided into lower boiling and higher boiling 45 hydrocarbons along with the pyrolytic reaction products. From the top of the products fractionator there was withdrawn, as by line 15, a vapor fraction comprising a blend of catalytically transformed and pyrolytically converted end point motor fuel and fixed gases made in the pyrolytic system. A clean light gas oil fraction was withdrawn from tower 2 by line 14, and a portion was removed for use as fuel oil while the remainder was sent by line 45 to be added to 50 the heavy condensate fraction in line 39 passing to cracking unit 11. A residual fuel comprising a heavy cracked tar was vented from the bottom of the tower by line 13. The overhead fraction 55 from products fractionator 2 when condensed and blended with the condensed overhead from crude fractionating column 1 yielded a distillate which required only a light caustic wash to provide a marketable motor fuel having an end point of approximately 410° F. and an octane rating of the order of 70 (C. F. R. M. M.) or better. It represented about 60% by volume of the original crude.

It is readily apparent from the above that the 75 present invention provides a unitary system em-

bodying the advantages of both the pyrolytic and catalytic systems while obviating the disadvantages of each. The difficultly vaporizable or heavy constituents in the charging stock are treated in a manner to realize the greatest yields 5 of high quality gasoline therefrom with an attendant minimum production of coky products having little or no value, while the easily vaporizable materials are handled to advantage. In addition to the above, substantial economies 10 and great flexibility of operation are secured.

I claim as my invention:

1. In the production of valuable motor fuels, the process comprising dividing original charging stock containing higher boiling hydrocarbons into 15 distillate and residual fractions, separately converting each fraction into motor fuel of the gasoline type in separate conversion zones maintained under conversion conditions, effecting stepwise cooling of products issuing from one of 20 said conversion zones to produce a plurality of condensate fractions of differing boiling ranges including a lower boiling condensate consisting essentially of desired motor fuel, admitting products issuing from the other of said zones substantially in vapor phase to a fractionating zone, withdrawing from the latter a fraction comprising motor fuel of the desired end point, and utilizing said lower boiling condensate as reflux in 25 said fractionating zone, thereby to assist in removing heat from the latter while simultaneously effecting fractionation of reaction products formed from said distillate and residual fractions. 30

2. In the production of lower boiling hydrocarbons, the process comprising separating into 35 a distillate fraction and a residual fraction a charging stock containing both difficultly vaporizable and easily vaporizable hydrocarbons, effecting conversion of said distillate fraction into desired lower boiling hydrocarbons in a pyrolytic 40 conversion zone maintained under pyrolytic conversion conditions, effecting conversion of said residual fraction into valuable lower boiling hydrocarbons in a catalytic conversion zone containing an adsorptive contact mass capable of 45 promoting cracking reactions and maintained under cracking conditions, subjecting products of conversion issuing from one of said zones to stepwise cooling to yield a plurality of condensates of differing boiling ranges including a lower boiling 50 condensate consisting essentially of desired lower boiling hydrocarbons, admitting the remainder of the conversion products in vapor phase to a fractionating zone, withdrawing a motor fuel fraction of desired end point from said fractionating 55 zone, and utilizing said lower boiling condensate as reflux in said fractionating zone, thereby simultaneously to assist in heat removal from and control of the latter and to produce a final fractionated motor fuel comprising a blend of pyrolytic and catalytic reaction products of desired 60 end point.

3. In the production of valuable lower boiling hydrocarbons of the motor fuel type the process of dividing a charging material containing both 65 difficultly vaporizable and easily vaporizable hydrocarbons into at least one distillate fraction comprising essentially easily vaporizable hydrocarbons and a residual fraction containing substantially all difficultly vaporizable material in 70 the charge, feeding the distillate fraction to a pyrolytic conversion zone maintained under suitable conditions for effecting conversion thereof into lower boiling hydrocarbons, removing reaction products from said conversion zone, feeding 75

said residual fraction to a catalytic reaction zone containing an adsorbent contact mass capable of promoting transformation thereof into lower boiling hydrocarbons and maintained under 5 transformation conditions, removing reaction products from said second reaction zone, admitting reaction products from said pyrolytic conversion zone to a fractionating zone adapted to separate lower boiling hydrocarbons from higher boiling hydrocarbons, dividing reaction products from the other of said zones into a plurality of fractions having relatively different boiling ranges, the lowest boiling range fraction comprising essentially lower boiling hydrocarbons of the motor fuel type, effecting substantial condensation of said lowest boiling range fraction, separating the resultant condensate from unden- 10 sioned material, and admitting said condensate as liquid to said fractionating zone to serve as reflux therein and to be fractionated along with the reaction products from the said pyrolytic conversion zone, thereby to minimize or avoid use of condensed overhead from said fractionating zone as reflux and to provide a blend of catalytically 15 and pyrolytically produced motor fuel.

4. In producing lower boiling hydrocarbons of the motor fuel type, the process comprising dividing charging material containing both easily vaporizable and difficultly vaporizable hydrocarbons into a distillate fraction and a residual fraction, effecting pyrolytic conversion of said distillate fraction under pyrolytic decomposition conditions into motor fuel products, vaporizing said residual fraction with the aid of a diluent fluid, 30 subjecting vapors so produced to catalytic cracking in a reaction zone containing porous adsorptive cracking catalyst maintained under vapor phase cracking conditions, subjecting pyrolytic reaction products to fractionation to yield a motor fuel fraction of the desired end point, dividing catalytic reaction products by successive 35 stages of partial condensation into at least two condensates of differing boiling ranges, the lower boiling condensate comprising essentially lower boiling hydrocarbons having the desired motor fuel boiling range, separating said diluent fluid from said lower boiling condensate, and utilizing the latter as reflux in said fractionating step, thereby to assist in the fractionation of said 40 pyrolytic products while simultaneously effecting fractionation of catalytically produced motor fuel to yield a final motor fuel of the desired boiling range comprising a blend of pyrolytic and catalytic products.

5. In the production of lower boiling hydrocarbons, the process comprising dividing a charging stock containing both difficultly vaporizable and easily vaporizable higher boiling hydrocarbons into a distillate fraction and a residual fraction, effecting pyrolytic conversion of said distillate 50 fraction under pyrolytic cracking conditions into motor fuel of the gasoline type, effecting catalytic cracking of said residual fraction with the aid of an adsorptive contact mass capable of promoting formation of high anti-knock motor fuels and maintained under cracking conditions, fractionating pyrolytic reaction products to yield a motor fuel fraction of controlled end point, dividing catalytic reaction products into a higher 55 boiling condensate and a lower boiling condensate, said lower boiling condensate comprising catalytically cracked motor fuel of the gasoline type, utilizing said lower boiling condensate as reflux in said fractionating step to assist in removal of heat from pyrolytic reaction products

and to assist in rectification of the latter while simultaneously rectifying catalytic reaction products and yielding a motor fuel of the desired end point comprising a blend of catalytically and pyrolytically cracked products, and effecting pyrolytic conversion of said higher boiling condensate. 5

6. In the production of valuable motor fuels, the process steps comprising dividing into a distillate fraction and a residual fraction a charging stock containing both difficultly vaporizable and easily vaporizable higher boiling hydrocarbons, effecting vapor phase conversion of said residual fraction into lower boiling hydrocarbons of the gasoline type with the aid of an adsorptive contact mass capable of promoting cracking reactions and maintained under cracking conditions, subjecting the resulting reaction products to stepwise cooling to produce a plurality of condensates including a lower boiling condensate 10 consisting essentially of desired motor fuel resulting from said conversion and a higher boiling condensate consisting essentially of hydrocarbons higher boiling than said motor fuel, effecting pyrolytic cracking of said higher boiling 15 condensate along with said distillate fraction, admitting products of said pyrolytic cracking to a fractionating zone, withdrawing from the latter a motor fuel fraction of the desired boiling range, and utilizing said lower boiling condensate as reflux in said fractionating zone, thereby to assist in the control of said fractionation and to yield a final motor fuel product comprising a blend of pyrolytically and catalytically converted 20 products. 25

7. In the production of valuable lower boiling hydrocarbons, the process of dividing a charging stock containing both easily vaporizable and difficultly vaporizable hydrocarbons into a distillate fraction and a residual fraction, effecting pyrolytic conversion of said distillate fraction, vaporizing a substantial portion of said residual fraction, transforming such vapors into valuable lower boiling hydrocarbons and clean higher boiling distillate with the aid of an adsorptive contact mass comprising essentially a blend of silica and alumina, passing reaction products of said pyrolytic conversion, to a fractionating zone, dividing the reaction products from the other of said fractions into a gas oil fraction, and a lower 30 boiling fraction comprising essentially desired lower boiling hydrocarbons, admitting at least a portion of said lower boiling fraction as liquid reflux to said fractionating zone, withdrawing a gas oil fraction from said fractionating zone, 35 effecting pyrolytic conversion of a portion of said gas oil fractions, and commingling the reaction products therefrom with the reaction products from said distillate fraction prior to the fractionation step. 40

8. In the production of valuable lower boiling hydrocarbons the process of dividing a charging material containing both difficultly vaporizable and easily vaporizable hydrocarbons into at least two clean distillate fractions of differing boiling 45 range, one relatively lower boiling and the other relatively higher boiling and a residual fraction containing substantially all difficultly vaporizable material in the charge, feeding the distillate fractions separately to a conversion zone 50 maintained under suitable conditions for effecting separate pyrolytic conversion of each into valuable lower boiling hydrocarbons of the motor fuel type, removing reaction products from said conversion zone, feeding said residual fraction to 55

a reaction zone containing an adsorbent contact mass capable of promoting transformation thereof into lower boiling hydrocarbons and clean higher boiling hydrocarbons having distillate characteristics and maintained under transformation conditions, removing reaction products from said second reaction zone, admitting the reaction products from the first-mentioned of said zones substantially in vapor phase to a fractionating zone adapted to separate lower boiling hydrocarbons from higher boiling hydrocarbons, cooling the reaction products from said second reaction zone in a series of steps to provide from said products a plurality of clean condensates having relatively different boiling ranges, the lowest boiling condensate comprising essentially lower boiling hydrocarbons, separating each condensate from uncondensed material, admitting said lowest boiling condensate as liquid to said fractionating zone to serve as reflux therein and to be fractionated along with the reaction products from the first mentioned one of said zones, feeding higher boiling condensate produced from said stepwise cooling of reaction products to said pyrolytic zone to be separately converted therein, and commingling reaction products from said pyrolytic zone prior to fractionation thereof.

9. In the production of valuable lower boiling hydrocarbons of the motor fuel type from charging material containing both easily vaporizable and difficultly vaporizable hydrocarbons, the process of dividing said charge into a plurality of clean distillate fractions and a residual fraction, one of said distillate fractions having the boiling range characteristics of gas oil, effecting separate conversion of said distillates into valuable lower boiling hydrocarbons of the motor fuel type in a reaction zone maintained under pyrolytic conversion conditions, vaporizing a substantial portion of said residual fraction with the aid of a diluent fluid, transforming such vapors into valuable lower boiling hydrocarbons and clean higher boiling hydrocarbons having distillate characteristics in a catalytic zone containing an adsorbent contact mass capable of promoting the desired transformation, withdrawing reaction products from each of said zones, admitting reaction products from said pyrolytic zone substantially in vapor phase to a fractionating zone adapted to separate desired lower boiling hydrocarbons from higher boiling hydrocarbons, dividing reaction products from said catalytic zone into a plurality of condensate fractions, one of said fractions comprising essentially desired lower boiling hydrocarbons, another of said fractions being a gas oil, removing said diluent fluid from said lower boiling condensate fraction feeding said lower boiling condensate to said fractionating zone to act as reflux therein and to be fractionated with the reaction products from said one of said zones, withdrawing from said fractionating zone a light gas oil fraction, and feeding one of said gas oil fractions to said pyrolytic reaction zone along with said first named gas oil fraction.

10. In the production of lower boiling hydrocarbons of the motor fuel type from charging material having substantially the boiling range characteristics of a whole crude oil, the process of dividing the charge into a plurality of distillate fractions including a heavy naphtha cut and a gas oil cut, and a residue, feeding said heavy naphtha cut and said gas oil cut to a pyrolytic reaction zone to be separately converted therein, effecting vaporization of said residue with the aid

of an inert diluent fluid, charging the vapors to a catalytic transformation system containing an adsorbent contact mass capable of promoting transformation thereof into lower boiling hydrocarbons of the motor fuel type and maintained under vapor phase transformation conditions, removing reaction products from each of said zones, admitting pyrolytic reaction products in substantially vapor phase to a fractionating zone, dividing catalytic reaction products into at least three condensates having relatively different boiling ranges, two of said condensates being relatively heavy and relatively light gas oils, the other containing substantially all the desired catalytically transformed motor fuel, separating said inert diluent fluid from said last named condensate, admitting the latter as liquid, to said fractionating zone to serve as reflux therein, withdrawing a desired end point motor fuel and a light gas oil fraction from said fractionating zone, commingling said light gas oil cut and said relatively heavy gas oil condensate, separately converting the resulting mixture in said pyrolytic zone, and adding said relatively light gas oil condensate to said fresh gas oil cut prior to conversion of the latter.

11. In apparatus for producing lower boiling hydrocarbons from charging material containing both easily vaporizable and difficultly vaporizable higher boiling hydrocarbons, in combination, a heater for fresh charge, a fractionating column connected to said heater adapted to effect separation of the charge into a distillate fraction and a residual fraction, a catalytic transformation system connected to said column adapted to receive said residual fraction and to transform the same into lower boiling hydrocarbons and clean higher boiling hydrocarbons having distillate characteristics, a pyrolytic conversion system also connected to said column adapted to receive said distillate fraction and to convert the same into lower boiling hydrocarbons, a second fractionating column adapted to separate desired lower boiling hydrocarbons from higher boiling hydrocarbons, a vapor connection from one of said systems to said last named fractionating column for conducting reaction products into the latter, means including a plurality of serially connected heat exchange means connected to the other of said systems for receiving reaction products therefrom adapted to effect condensation of said reaction products in a succession of controlled steps thereby to produce a plurality of condensates having differing boiling ranges, means for separating said condensates from uncondensed material and means for conducting the lowest boiling of said condensates from said separating means as liquid to the upper portion of said second fractionating column to serve as reflux therein.

12. In apparatus for producing lower boiling hydrocarbons from charging material containing both easily vaporizable and difficultly vaporizable higher boiling hydrocarbons, in combination, a heater for fresh charge, a fractionating column connected to said heater adapted to receive fresh charge and to effect separation of the same into a distillate fraction and a residual fraction, a catalytic transformation system connected to said column adapted to receive said residual fraction and to transform the same into lower boiling hydrocarbons and clean higher boiling hydrocarbons having distillate characteristics, a pyrolytic conversion system also connected to said column adapted to receive said distillate fraction and to convert the same into lower boiling hydrocarbons, a second fractionating column adapted to sepa-

- rate lower boiling hydrocarbons from higher boiling hydrocarbons, a vapor connection from said pyrolytic system to said last named fractionating column for conducting pyrolytic reaction products into the latter, means including a plurality of serially connected heat exchange means connected to said catalytic system for receiving reaction products therefrom adapted to effect condensation of said reaction products in a succession of controlled steps thereby to produce at least one higher boiling condensate of the gas oil type and a lower boiling condensate comprising essentially desired lower boiling hydrocarbons, and means including a conduit connection for conducting said lower boiling condensate from said first named means to the upper portion of said second fractionating column to serve as reflux therein.
13. In apparatus for producing lower boiling hydrocarbons from charging material containing both easily vaporizable and difficultly vaporizable higher boiling hydrocarbons, in combination, a heater for fresh charge, a fractionating column connected to said heater adapted to effect separation of the charge into a distillate fraction and a residual fraction, a catalytic transformation system connected to said column adapted to receive said residual fraction and to transform the same into lower boiling hydrocarbons and clean higher boiling hydrocarbons having distillate characteristics, a pyrolytic conversion system also connected to said column adapted to receive said distillate fraction and to convert the same into lower boiling hydrocarbons, a second fractionating column adapted to separate desired lower boiling hydrocarbons from higher boiling hydrocarbons, a vapor connection from one of said systems to said last named fractionating column for conducting reaction products into the latter, means including a plurality of serially connected heat exchange means connected to the other of said systems for receiving reaction products therefrom adapted to effect condensation of said reaction products in a succession of controlled steps thereby to produce a higher boiling condensate of the gas oil type and a lower boiling condensate comprising chiefly gasoline, means for separating said lower boiling condensate from uncondensed material, a connection for conducting said higher boiling condensate from said first named means to said pyrolytic system, and means including a line for conducting said lower boiling condensate from said separating means to the upper portion of said second fractionating column to serve as reflux therein.
14. In apparatus for producing lower boiling hydrocarbons from charging material containing both easily vaporizable and difficultly vaporizable higher boiling hydrocarbons, in combination, a heater for fresh charge, a fractionating column connected to said heater adapted to effect separation of the charge into a distillate fraction and a residual fraction, a catalytic transformation system connected to said column adapted to receive said residual fraction and to transform the same into lower boiling hydrocarbons and clean higher boiling hydrocarbons having distillate characteristics, a pyrolytic conversion system also connected to said column adapted to receive said distillate fraction and to convert the same into lower boiling hydrocarbons, a second fractionating column adapted to separate desired lower boiling hydrocarbons from higher boiling hydrocarbons, a vapor connection from one of said systems to said last named fractionating column for conducting reaction products into the

latter, means including a plurality of serially connected heat exchange means connected to the other of said systems for receiving reaction products therefrom adapted to effect condensation of said reaction products in a succession of controlled steps thereby to produce at least one higher boiling condensate of the gas oil type and a lower boiling condensate, means for separating said lower boiling condensate from uncondensed material, means including a conduit connection for conducting separated condensate from said separating means to the upper portion of said second fractionating column to serve as reflux therein, an outlet connection on said second fractionating column for withdrawing therefrom a clean higher boiling fraction, and means including conduits for selectively conducting said higher boiling fraction and said higher boiling condensate from said outlet and said heat exchange means to said pyrolytic system.

15. In apparatus for producing lower boiling hydrocarbons from charging material containing both easily vaporizable and difficultly vaporizable hydrocarbons, in combination, a heater for fresh charge, a fractionating column connected to said heater adapted to effect separation of the charge into a distillate fraction and a residual fraction, a heater for receiving and vaporizing said residual fraction, means for adding inert diluent fluid to said fraction to assist in said vaporization, a converter containing an adsorbent contact mass capable of promoting transformation of said vaporized residue into lower boiling hydrocarbons, means for conducting vapors from said heater to said converter, a plurality of serially connected heat exchange means connected to said converter adapted to receive reaction products therefrom and to produce a higher boiling condensate of the gas oil type and a lower boiling condensate, means associated with said heat exchange means for separating said inert diluent fluid from said lower boiling condensate, a pyrolytic conversion system connected to said fractionating column adapted to receive said distillate fraction and to convert the same into valuable lower boiling hydrocarbons, a second fractionating column, a vapor connection between said pyrolytic system and said second column, and a line for conducting said lower boiling condensate from said separating means as liquid and freed of inert diluent to said second fractionating column to serve as reflux therein.

16. In apparatus for producing lower boiling hydrocarbons from charging material containing both easily vaporizable and difficultly vaporizable hydrocarbons, in combination, a heater for fresh charge, a fractionating column connected to said heater adapted to effect separation of the charge into a distillate fraction and a residual fraction, a heater for receiving and vaporizing said residual fraction, means for adding steam to said fraction to assist in said vaporization, means connected to said second named heater for separating and removing unvaporized residue from vapors, a catalytic converter, a line for conducting said vapors from said separating means to said converter, means in said line for adding additional steam to said vapors, a plurality of serially connected heat exchange means connected to said converter adapted to receive reaction products therefrom to produce a plurality of roughly fractionated condensates, means connected to the last of said heat exchange means for separating and removing condensed steam and uncondensable gases from the lowest boiling condensate, a pyro-

lytic conversion system connected to said fractionating column adapted to receive said distillate fraction and to convert the same into valuable lower boiling hydrocarbons, a second fractionating column, a vapor connection between said pyrolytic system and said second column, and a line for conducting said lowest boiling condensate from said separating means as liquid and freed of condensed steam and gases to said second fractionating column to serve as reflux therein.

17. In apparatus for producing lower boiling hydrocarbons from charging material containing both easily vaporizable and difficultly vaporizable hydrocarbons, in combination, a heater for fresh charge, a fractionating column connected to said heater adapted to effect separation of the charge into a distillate fraction and a residual fraction, a heater for receiving and vaporizing said residual fraction, means for adding inert diluent fluid to said fraction to assist in said vaporization, a converter containing an adsorbent contact mass capable of promoting transformation of said vaporized residue into lower boiling hydrocarbons, means for conducting said vapors to said converter, a plurality of serially connected heat exchange means connected to said converter adapted to receive reaction products therefrom to produce a plurality of roughly fractionated condensates, steam stripping means connected with certain of said heat exchangers for stripping roughly fractionated condensate of entrained lower boiling hydrocarbons, means for separating condensed steam and fixed gases from the lowest boiling condensate, a pyrolytic conversion system connected to said fractionating column adapted to receive said distillate fraction and to convert the same into valuable lower boiling hydrocarbons, a conduit connection for conducting stripped condensate from said steam stripping means to said pyrolytic conversion system, a second fractionating column, a vapor connection between said pyrolytic system and said second column, and a line for conducting said lowest boiling condensate as liquid and freed of condensed steam and gases from said separating means to said second fractionating column to serve as reflux therein.

18. In apparatus for producing lower boiling hydrocarbons from charging material containing both easily vaporizable and difficultly vaporizable higher boiling hydrocarbons, in combination, a heater for fresh charge, a fractionating column connected to said heater adapted to effect separation of the charge into a plurality of distillate fractions and a residual fraction, a catalytic transformation system connected to said column adapted to receive said residual fraction and to transform the same into lower boiling hydrocarbons and clean higher boiling hydrocarbons having distillate characteristics, a plurality of pyrolytic systems connected to said column so as selectively to receive said distillates for converting the same into lower boiling hydrocarbons of the motor fuel type, a second fractionating column, lines for selectively connecting said pyrolytic systems and said second column, means including a plurality of serially connected heat exchange means connected to said catalytic system for receiving reaction products therefrom adapted to effect condensation of said products in a succession of controlled steps thereby to produce at least one higher boiling condensate comprising essentially clean hydrocarbons of the gas oil type and a lower boiling condensate comprising essentially desired lower boiling hydrocarbons, means for removing said condensates from uncondensed material, a line for conducting said lower boiling condensate to said fractionating column and introducing it into the upper portion thereof to serve as reflux therein, a line for withdrawing from said second column a higher boiling fraction comprising clean gas oil, a connection for conducting said higher boiling condensate to one of said pyrolytic systems, and means for selectively conducting said higher boiling fraction to one of said pyrolytic systems and said last named connection.

ARTHUR E. PEW, JR.
